DES. 1949

Charles St. Nicholas, of New York, N.Y.

Assignee to

Chas Wood, Chas. Hughes and Stephen Fabius, of the same place.

Letter Patent 1,519,444. Dated June 7, 1864.

Design for a Spoon or Fork Handle.

The schedule referred to in these Letters Patent and making part of the same.

To all whom it may concern:

Be it known that I, Charles St. Nicholas, of the City, County and State of New York, have produced a new and ornamental Design for Handle of Spoons, Forks, etc.; and I do hereby declare that the following is a full, clear and exact description thereof which will enable others skilled in the art to make and apply the same, reference being had to the accompanying drawing forming part of this specification, in which:

Fig. 1 represents a front elevation of my design.

Fig. 2. a rear elevation of the same.

Similar letters of reference indicate like parts.

This design consists in a series of arabesques converging towards a leaf and joined by two convolutes and dragons tails on the surface near the outer end of the handle, and a series of similar arabesques surrounding an oval escutcheon or medall and joined by two convolutes and dragons tails on the under surface of the handle near its outer end and with a heart-shaped escutcheon ornamented by suitable leaves on the under surface of said handle at or near its juncture with the bowl or body of the spoon fork or other article to which said handle is attached, in such a manner that a beautiful and ornamental design is produced: The effect of this design is further increased by fluting the handle on the upper and lower surface from the ornaments at the top end to the juncture of the same with the bowl or body of the spoon fork or other article.

similar arabesques surrounding an oval escutcheon or medal and joined by two convolutes and dragons tails on the under surface of the handle near its outer end and with a heart shaped escutcheon ornamented by suitable leaves on the under surface of said handle at or near its juncture with the bowl or body of the spoon fork or other article to which said handle is attached, in such a manner that a beautiful and ornamental design is produced: The effect of this design is further increased by fluting the handle on the upper and lower surface from the ornaments at the top end to the juncture of the same with the bowl or body of the spoon fork or other article.

A. represents the handle which is ornamented on its upper surface by a series of arabesques a, converging towards the leaves b, and joined by the convolutes and dragons tails, one on either edge of the handle. The stalk of the leaves b, extends down between the convolutes and dragons tails c, and it terminates in the flute d, which is made in the upper surface of the handle and extends down to its junction with the bowl or body of the spoon, fork or other article to which said handle may be attached.

The under side of the handle is ornamented by a series of arabesques a', which emanate from under the escutcheon b' and are joined by two convolutes & dragons tails c', to those on the upper surface.

The escutcheon b' is supported by the calyx d', the stem of which extends down between the convolutes and dragons tails c', and it terminates in the flute d.* This flute

DES. 1949

forms the connection between the ornaments on the outer and those on the inner end of the handle.

The ornaments on the inner end of the handle consist of a heart shaped escutcheon *e.* the face of which is occupied by a series of leaves *f.* and two spear shaped heads *g. h.* extend from the same towards the outer end of the handle.

It is obvious that this handle is applicable to spoons of any description or to forks or other similar articles and when properly made and burnished it produces a striking effect.

Having thus described my invention, I claim as new and desire to secure by Letters Patent.

The design for a spoon or other handle as shown and described.
